SAFETY MECHANISM FOR UNCOUPLING A
SHAFT FROM THE DRIVING MEMBER OF
A MACHINE

Adrianus van Haandel, deceased, late of Helmond, Netherlands, by Johannes Hubertus van Haandel, legal representative, Helmond, Netherlands, assignor to Nedschroef Octrooi Maatschappij N. V., Helmond, Netherlands, a company of the Netherlands

Application March 13, 1951, Serial No. 215,399
In the Netherlands March 16, 1950

8 Claims. (Cl. 192—129)

1

This invention relates to improvements in safety mechanisms or devices of the type employed for uncoupling or declutching a driven shaft from the driving member of a machine, such as a crank-shaft or an eccentric type press.

More particularly, the invention relates to such a machine including a coupling member or sliding key extending parallel to the axis of the shaft into engagement with the driving member, the coupling member being maintained in coupled position by a spring and being moved out of coupling position by the action of a wedge-shaped member movable into the path of the key when the machine is in operation.

The primary object of the present invention is to provide a safety mechanism which will be operable automatically upon the occurrence of a default in the machine.

A further object of the invention is to provide a safety mechanism for machines of the type referred to which will be operable automatically with a minimum of movement and power on the occurrence of a default, such as a stoppage in the supply of material to the machine.

In accordance with the invention, the improvements are applied to safety mechanisms of the type referred to and include means operable on rotation of the shaft for rocking the wedge-shaped member into and out of the path of the coupling member or key without normally causing the wedge-shaped member to engage the coupling member or key, and means responsive to the occurrence of a fault in the operation of the machine for retaining the wedge-shaped member in its rocked position in the path of the coupling member or key, whereby the wedge-shaped member engages the coupling member or key and the latter is moved out of its coupling position with respect to the driving member.

In a preferred construction, the safety mechanism includes a cam carried by the shaft for rocking the wedge-shaped member to its uncoupling position, and a tongue, or stop, movable into a position to hold the wedge-shaped member in its uncoupling position.

In this construction the tongue or stop is operated in response to some default in the operation of the machine so that it is moved into the path of the wedge-shaped member to hold it in its uncoupling position. Very little power is, therefore, required for effecting the uncoupling of the shaft from the driving member since the wedge-shaped member is periodically rocked into uncoupling position by the cam carried by the shaft.

The invention includes other features as de-

5 scribed in the following detailed description of illustrative embodiments of the invention, as shown in the accompanying drawings forming a part of this application.

2

In the drawings:

Fig. 1 is a broken side elevational view of a part of a machine including a shaft coupled to a driving member, the construction being of the type to which the safety mechanism of the present invention is applied;

Fig. 2 is a front elevational view, partly in section taken on the line II—II of Fig. 1, showing the elements of the safety mechanism in unactuated position;

Fig. 3 is a view similar to that of Fig. 1, showing the shaft uncoupled from the driving member;

Fig. 4 is a view similar to that of Fig. 2 taken on the line IV—IV of Fig. 3, showing the safety mechanism in actuated position;

Fig. 5 is a broken plan view of a part of the mechanism shown in Figs. 2 and 4;

Fig. 6 is a sectional view taken on the line VI—VI of Fig. 5; and

Fig. 7 is a front elevational view similar to that of Fig. 4, showing a modified form of construction including a braking means.

In Figs. 1 to 4 of the drawings, the machine therein shown comprises a shaft 1 which may be a crank-shaft or a shaft for driving an eccentric. A coupling sleeve 2 is keyed to the shaft 1 by means of the key 3 and a rotatable driving member, such as a fly wheel 4 is carried on the shaft 1 adjacent to the coupling sleeve 2. The fly wheel 4 is rotatable on the shaft, but is coupled or keyed thereto by means of a sliding coupling member or key 5 normally carried in the sleeve 2 parallel to the shaft 1, the key 5 being biased into engagement with the fly wheel 4 by a spring 6. The key 5 engages in a hole 7 in the hub of the flywheel 4 thereby effecting the coupling of the wheel 4 to the shaft 1.

The means for uncoupling the shaft and fly wheel, that is, the means for shifting the key 5 against the action of the spring 6, comprises a bell-crank lever 8 pivoted on the frame of the machine by a pin or shaft 9, this shaft 9 being parallel to the axis of the shaft 1. The lever 8 includes an arm 10 extending under the shaft 1, the end of which is biased toward the shaft by a compression spring 11 supported at a fixed point in the frame of the machine. The lever 8 also includes an arm 12 extending generally at right angles to the arm 10 and which is arranged to engage in a slot in the slidable key 5.

In accordance with the present invention, a roller 13 is mounted on the arm 10 in a position to engage the peripheral surface of a cam 14, comprising a disc-like member having a cam surface mounted in spaced relation to the sleeve 2 and keyed to the shaft 1 by the key 3. The cam member 14, including the disc-like member, may be made as an integral part of the sleeve 2 and have essentially the hub and other structure shown in Figs. 1 to 4 of the drawings.

The shape of the cam 14 is shown in Figs. 2 and 4 of the drawings and is such that the arms 10 and 12 are rocked at each revolution of the shaft 1 so that the upper end of the arm 12 is moved toward the shaft and then under normal conditions released so that it is rocked away from the shaft in time to miss the pin 5 in its rotation about the axis of the shaft 1.

The upper end of the arm 12 is provided with a wedge-shaped end portion 15 having an inclined surface 16, which is arranged to engage an inclined surface 11 of the slot and which fits an inclined surface 11 of the slot in the outer surface of the key 5, as shown in Fig. 1 of the drawings. If the arm 12 is held at its innermost position with respect to the shaft 1 to which it is moved by the wider portion of the cam 14, the surface 17 engages the surface 16 to shift the key 5 to the right, to the position shown in Fig. 3. This action takes place against the biasing force of the spring 6, and the shaft 1 is uncoupled from the drive wheel 4.

In order to effect the uncoupling or declutching operation according to the invention, a means is provided which is responsive to the occurrence of some default in the operation of the machine for retaining the arm 12 in its uncoupling position. This mechanism comprises a guide 18 mounted on the frame of the machine adjacent to the cam 14 and serving to guide a tongue or stop 19 into the path of a spacer lug 31 mounted on the back of the arm 12. This arrangement is shown in Figs. 2, 4, 5 and 6. The tongue or stop 19 is reciprocated by a lever 20 having a pin 34 engaging in an arcuate slot in the guide 18 and in a vertical slot in the stop 19, the lever 20 being fixed to a shaft 21 carried in bearings 35. The opposite end of the shaft 21 from the arm 20 carries an arm 36 which is attached to any suitable means connected up to one or a number of parts of the machine for actuation in the event of the occurrence of a default, such as a slowing down in the supply of material or the actual stoppage of material supply to the machine.

In the operation of the safety mechanism shown in Figs. 1 to 6, the bell-crank lever 8 is continuously rocked by the cam 14 as the shaft 1 is rotated. When a fault occurs, the tongue or stop 19 is slipped into the path of the arm 12 comprising the wedge-shaped abutting member so that it is blocked from moving away from the shaft 1. The key 5, therefore, moves into engagement with the arm 12 as shaft 1 rotates, the lower portion of the key, as seen in Fig. 3, engaging a shoulder or abutment 22 on the arm 12, stopping the rotation of the shaft 1. In restarting the machine after the fault has been corrected, the shaft 21 must be rotated in reverse to a small extent and the stop 19 retracted in order to permit the spring 11 to pivot the lever 8, thereby permitting the key 5 to engage in the hole 1 of the drive wheel 4 under the biasing action of the spring 6.

In order to aid in stopping the rotation of the shaft 1 when it is to be uncoupled by the safety mechanism described above, the braking arrange-

ment shown in Fig. 7 is combined with the uncoupling mechanism. In this figure the parts of the apparatus, which correspond to those shown in Figs. 1 to 6 are referred to by the same reference characters plus the letter a.

In Fig. 7 the apparatus includes a braking disc or drum 23 keyed to the shaft 1 and a brake band 24 extending around the disc and attached at one end 29 to the arm 10 of the rocking lever 8. The periphery of the coupling sleeve 2 may be employed as the braking disc. The shaft 1 carries a cam 25 used for actuating the brake band 24, this cam being engaged by a roller 27 mounted on arm 26 of a bell-crank lever pivoted on a pin or shaft 32, and having a second arm 28 extending laterally and biased by a compression spring 33. The spring 33 rocks the arm 26 to maintain engagement of the roller 27 with the cam 25. The opposite end 30 of the brake band 24 is attached to the end of the arm 28 by means of an adjustable connection 31. The cam 25 may be mounted adjacent the cam 14a and on the same mounting.

Since the brake band 24 is attached to the arm 10a, it is pulled somewhat at every movement of the arm 12a in the direction of the shaft 1a, but at that time the roller 27 is not in contact with the cam 25. The position of the cam 25 is selected so that under normal conditions it effects pulling of the brake band 24 when the roller 13a is in the low part of the cam 14a and the arm 12a is free from engagement by the key 5a, or when the end 15a has passed the coupling member 5.

However, when the tongue 19a blocks the movement of the arm 12a and retains it in the uncoupling position, the pull on the brake band 24 by the arm 10a is retained, and as the key 5a is being moved to its uncoupled position, the cam 25 engages the roller 27 to further tighten up on the brake band 24 so that the shaft 1 is braked effectively during the action of the uncoupling mechanism, thereby stopping the shaft 1 less abruptly and causing the application of less pressure on the shoulder or abutment 22a of the uncoupling arm 12a.

The safety mechanism has the advantage that the uncoupling arm 12 is constantly moved into a position to effect the uncoupling of the fly wheel and the stopping of the shaft 1 at any instant upon the happening of a fault in the operation of the machine. Such an uncoupling, however, does not become effective, and the arm 12 is always moved out of its uncoupling position, unless the arm is blocked by the tongue or stop 19.

Various known types of means may be employed for operating the shaft 21 from various parts of the machine in response to the occurrence of a faulty operation so as to effect stopping of the machine. Such means are well known in the art and need not be described in connection with the actual safety mechanism claimed in the present application. Furthermore, such means will effectively move the tongue 19 with the use of very little power.

What is claimed as new is:

1. In a safety mechanism for disengaging a coupling between a shaft and the driving member of a machine including a coupling member slidable parallel to the shaft, means for biasing the coupling member to coupling position, and a wedge-shaped member movable into the path of the coupling member for engaging and moving it out of its coupling position, the improvement comprising means for biasing said wedge-shaped member away from the path of the coupling member, means operable on rotation of the shaft

for rocking said wedge-shaped member into the path of said coupling member without normally causing said wedge-shaped member to engage said coupling member, means responsive to the occurrence of a fault in the operation of the machine for retaining the wedge-shaped member in its rocked position in the path of said coupling member, whereby the wedge-shaped member is engaged by the coupling member and the latter moved out of coupling position, a braking means operable on the shaft and interconnected with said wedge-shaped member, and means operable for applying said braking means when the wedge-shaped member is retained in its uncoupling position and engaged by the coupling member.

2. In a machine including a shaft to be driven, a driving member for the shaft, a slidable key carried by the shaft for coupling the shaft to the driving member, means biasing the key to its coupling position, and a safety mechanism including a pivoted arm to be engaged by the key for sliding it out of engagement with the driving member, the improvement comprising a cam, carried by the shaft, for rocking said arm into its uncoupling position at a point in advance of that at which it would be engaged by said key, means for biasing said arm away from its uncoupling position, and a stop means operable in response to the occurrence of a fault in the operation of the machine for retaining said arm in its uncoupling position when moved thereto by said cam, whereby said arm is engaged by said key and the key shifted out of engagement with the driving member.

3. A machine as claimed in claim 2, including a brake disc attached to the shaft, a brake band engaging the periphery of said disc and having one end interconnected with said pivoted arm and pulled thereby when said arm is rocked to its uncoupling position, and means operatively associated with the shaft and operated by rotation of said shaft for pulling on the opposite end of said band when the key is moved by rotation of the shaft to its engagement position with respect to said arm.

4. A machine as claimed in claim 3, in which the means operated by rotation of the shaft comprises a bell-crank lever one arm of which is attached to said opposite end of the brake band, a second cam carried by said shaft, and a roller on the other arm of said bell-crank lever in a position to be engaged by said second cam.

5. A machine as claimed in claim 4, in which the pivoted arm of the safety mechanism comprises one arm of a pivoted bell-crank lever, the said one end of the brake band being connected to the other arm of the pivoted bell-crank lever.

6. A machine as claimed in claim 2, including means for stopping rotation of the shaft when the slidable key is in engagement with the pivoted arm.

7. A machine as claimed in claim 2, in which the pivoted arm includes means cooperating with the key for stopping rotation of the shaft when said pivoted arm is engaged by the slidable key.

8. In a safety mechanism for disengaging a coupling between a shaft and the driving member of a machine including a coupling member slidable parallel to the shaft, means for biasing the coupling member to coupling position and a wedge-shaped member movable into the path of the coupling member for engaging and moving it out of its coupling position, the improvement comprising means for biasing said wedge-shaped member away from the path of the coupling member, means operable on rotation of the shaft for rocking said wedge-shaped member into the path of said coupling member without normally causing said wedge-shaped member to engage said coupling member, means responsive to the occurrence of a fault in the operation of the machine for retaining the wedge-shaped member in its rocked position in the path of said coupling member, whereby the wedge-shaped member is engaged by the coupling member and the latter moved out of coupling position, a brake band operable on the shaft, one end of said brake band being interconnected with said wedge-shaped member and arranged to be pulled when said wedge-shaped member is rocked to its uncoupling position, a rocker shaft to which the other end of said brake band is attached, and a cam carried by the shaft and positioned to actuate said rocker shaft to pull the brake band when the coupling member is in its engagement position with respect to the wedge-shaped member.

JOHANNES HUBERTUS VAN HAANDEL,
